ARTHUR W. HARRISON AND EUGENE H. FOSDICK, OF LOS ANGELES,
CALIFORNIA.

TROLLEY-POLE CONTROLLER.

SPECIFICATION forming part of Letters Patent No. 779,401, dated January 3, 1905.

Application filed June 2, 1904. Serial No. 210,851.

To all whom it may concern:

Be it known that we, ARTHUR W. HARRISON and EUGENE H. FOSDICK, citizens of the United States, residing at Los Angeles, in the county of Los Angeles and State of California, have invented new and useful Improvements in Trolley-Pole Controllers, of which the following is a specification.

Our invention relates to controllers for trolley-poles used with an overhead feed-wire; and the object thereof is to provide means whereby the trolley-wheel will be held in engagement with the overhead feed-wire with a constant and uniform pressure of the trolley-wheel upon the feed-wire and when the trolley-wheel accidentally leaves the wire will cause the same to fall below the span-wires. We accomplish this object by the mechanism shown herein and illustrated in the accompanying drawings, in which—

Figure 1 is a diagrammatic view, with certain of the parts in elevation and certain of the parts in central vertical section, of the base and lower portion of the trolley-pole. Fig. 2 is a side elevation of a part of the upper portion of a trolley-pole and a portion of the feed-wire. Fig. 3 shows a three-way valve.

In the drawings, A is the base-block, which is secured upon the top of the car. (Not shown.) In the center of this block is a circular air-chamber B, which is connected by pipe C with a suitable compressed-air supply. (Not shown.) This pipe is insulated from the base by insulation C. In this air-chamber is a soft-iron plunger D, which forms the plunger of the compound-wound solenoid-magnet E, which has a section E' of the core on which the wire is wound of bronze. The section E' is made of bronze or other non-magnetic material to separate the pole-pieces. This plunger has a hollow cylindrical chamber F therein, the lower end of which tapers to a point, so that as the plunger is raised in the magnet the power thereof may be uniform. In this chamber is mounted a spiral spring H, which bears against a follower I, mounted in the chamber. This follower supports the pitman-rod J, whose upper end is pivotally connected at K

to the trolley-pole L. The trolley-pole is pivoted at 1 to the cap 2, which cap is bolted to the flanged ring 3, that passes under the flange E' of the solenoid-core. These flanges form a ball-race in which are balls 4, which provide a ball-bearing joint between the cap and solenoid. The pitman is secured from separation from the plunger by a plate M, secured to the plunger, through which plate it passes, the rounded head J' preventing it from passing through said plate. Magnet E has a winding N, which is connected in series to the motor O by line P. The magnet is also provided with a shunt-winding Q, which is connected to the core at 5 and by line 6 with ground c. The upper end of the trolley-pole is provided with the ordinary trolley-wheel R, which engages the feed-wire S, and the supplemental contact-wheel T, which also engages the feed-wire. This supplemental wheel is carried by an L-shaped arm U, which is pivoted to bearing-arm V, which arm is insulated from the pole by insulation W. This arm is connected, through line X, having resistance Y therein, to the trolley-pole. A spring a, connected to arm U and bearing-arm V, holds this wheel-spring pressed against the wire. The motor is connected by line b to ground c. The other end of the series winding is connected by line d with the base. Non-inductive resistance e is connected across the shunt-winding to prevent inductive kick when the trolley-wheel accidentally leaves the feed-wire.

In the operation of our device the compressed air is turned into the air-chamber B by means of the three-way valve f on pipe C, which valve is located at a convenient position to be operated by the conductor or motorman, and by means of the ordinary rope g the trolley-wheels are guided to the feed-wire. As soon as the wheels are on the feed-wire the magnet is energized, and the air is then cut off at the valve and chamber B opened to the atmosphere. Thereafter as long as the wheels are in contact with the feed-wire pressure is maintained between them by the magnet. When the motors are not being operated, the current through the series winding is cut off

and there is but slight pressure between the wheels and the feed-wire, which is produced by the magnetism of the shunt-winding; but as soon as the motors are operated the pressure is increased to the required degree by the series winding. If at any time the wheels accidentally leave the feed-wire, the circuit through the magnet is broken and the wheels fall of their own weight, as counterbalancing-weight 10 *h* is not quite heavy enough to balance the wheel end of the pole.

The purpose of providing the supplemental wheel *T* is to prevent the magnet from becoming inert when the wheel *R* is on a circuit-breaker *i*, as shown in Fig. 2.

Having described our invention, what we claim as new, and desire to secure by Letters Patent, is—

1. A trolley-pole controller comprising a base having an air-chamber therein; a solenoid-magnet secured to said base; a plunger for said magnet projecting into and forming a piston in said air-chamber; a cap rotative upon said magnet; a trolley-pole pivotally secured to said cap; a pitman pivotally secured to said trolley-pole and operatively connected to the magnet-plunger; 20
2. A trolley-pole controller comprising a base having an air-chamber therein; a solenoid-magnet having a series winding running through the motor to the ground, and a shunt-winding running to ground, said magnet being secured to said base; a plunger having a chamber in the upper end thereof for said magnet, said plunger projecting into and forming a piston in said air-chamber; a cap rotatively secured upon said magnet; a trolley-pole pivotally secured to said cap; a pitman pivotally secured to the trolley-pole and operatively connected to the magnet-plunger; 30
- 35
- 40

3. A trolley-pole controller comprising a base having an air-chamber therein; a solenoid-magnet having a series and a shunt winding secured to said base; a plunger for said magnet projecting into and forming a piston in said air-chamber; a cap rotatively secured upon said magnet; a trolley-pole pivotally secured to said cap; a trolley-wheel on the end of said pole; a supplemental contact-wheel secured to said pole near the end thereof and insulated therefrom; a line having resistance therein connecting the supplemental contact-wheel with said pole; a pitman pivotally secured to said trolley-pole and operatively connected to the magnet-plunger. 45

4. In a trolley-pole controller in which the pressure of a trolley-wheel upon the feed-wire is caused by magnetic force, a supplemental contact-wheel secured to the trolley-pole near the end thereof and insulated therefrom; a line having resistance therein connecting said supplemental contact-wheel with said trolley-pole. 50

5. In a trolley-pole controller in which the trolley-wheel is held in contact with the feed-wire by magnetic force a solenoid-magnet having a plunger, said plunger having a chamber therein, a spring in said chamber, a follower in said chamber above said spring; a trolley-pole, a pitman secured thereto and resting on said follower. 65

In witness that we claim the foregoing we have hereunto subscribed our names this 26th day of May, 1904.

ARTHUR W. HARRISON,
EUGENE H. FOSDICK.
